(57) **CLAIM**

I claim the ornamental design for an automobile wheel, as shown and described.

DESCRIPTION

FIG. 1 is a perspective view of an automobile wheel according to the claimed design; and,

FIG. 2 is a front elevational view of the automobile wheel according to the claimed design.

The ornamental design which is claimed is shown in solid lines in the drawings. The broken lines shown in FIG. 1 illustrate portions of the automobile wheel that form no part of the claimed design.

1 Claim, 2 Drawing Sheets

FIG. 1

FIG. 2
